UNITED STATES PATENT OFFICE.

ADOLPH RIPPEN, OF READING, PENNSYLVANIA, ASSIGNOR TO WILLIAM M. GRISCOM, MATTHAN HARBSTER, AND WILLIAM HARBSTER, ALL OF SAME PLACE.

APPLE-PARER.

SPECIFICATION forming part of Letters Patent No. 269,117, dated December 12, 1882.

Application filed November 28, 1881. (Model.)

To all whom it may concern:

Be it known that I, ADOLPH RIPPEN, a citizen of the United States, residing in Reading, Berks county, Pennsylvania, have invented 5 certain Improvements in Apple-Parers, of which the following is a specification.

My invention relates to certain improvements in the class of apple-parers in which the fork-shaft has a longitudinal movement and 10 is combined with a paring-knife so hung as to follow the contour of the apple, and with blades which effect the coring and slicing of the apple as the latter is rotated and fed forward, the objects of my invention being, first, to permit the ready removal of the apple from the coring tube; second, to provide for the thorough 15 paring of the apple; third, to throw the paring and slicing devices, or either of them, out of operation when their use is not required.

20 In the accompanying drawings, Figure 1, Sheet 1, is a side view of my improved apple-paring machine; Figs. 2 and 3, Sheet 2, sections on the line 1 2 of Fig. 1, with the parts in different positions; Figs. 4 and 5, views of 25 part of the machine on the opposite side from that shown in Fig. 1; and Figs. 6 and 7, Sheet 1, views of the paring-knife.

20 A is the main frame of the machine, which has at one end and on the under side a screw-clamp, A', whereby it is secured to the edge 30 of a table, shelf, or other suitable support, the opposite end of the frame having on the upper side a standard, A², on which are formed bearings a for the shaft B, the latter having at one 35 end the usual fork, B', for holding the apple and at the opposite end an operating-crank, B², said shaft being free to turn and to slide longitudinally in its bearings a.

30 Lugs on one side of the frame A carry a shaft, 40 b, to which is journaled a frame, D, and to the latter is swiveled the knife-arm E, the knife d being secured to the upper end of the latter and projecting through a slot therein, so as to bear against an apple placed upon the fork B', the knife being caused to press constantly 45 against the surface of the apple by the action upon the frame D of a coiled spring, e, and being free to follow the contour of the apple

as the latter is moved forward by the fork-shaft, the swiveled arm turning so as to present the 50 knife at the proper angle, and the frame D being vibrated laterally as the diameter of the apple varies.

A paring device substantially similar to the above has long been known and used, and this 55 device in itself forms no part of my invention; but in my machine I have combined with the paring device a cam-lever, F, which is pivoted to a lug, f, on the frame A, so that when it is in the position shown in Figs. 1 and 2 the knife-arm and frame D are free to act, as usual, under control of the spring e; but when the lever F is turned, by means of its arm g, to the position shown in Fig. 3, the cam g' acts upon the frame D and causes the latter to turn on the shaft b, 60 so as to carry the knife d outward and away from the surface of an apple placed on the fork B', whereby the machine can be thrown out of gear when it is desired to core or core and slice 65 the apple without paring the same.

The coring and slicing devices comprise the tube G and vertical knife H, the tube G having at the front end a flange, i, forming a screw-thread or section of a screw-thread, so that when an apple carried by the fork B' is pressed 70 against the front end of the tube and the shaft B is rotated the flange i will take a hold upon the apple, and will, owing to its screw-like character, cause said apple and the fork-shaft to be drawn forward as they are rotated, the 75 core being contained within the tube. At the same time the apple is cut into a spiral slice by the action of the knife H, and after the operation is completed the fork-shaft is withdrawn, the flange i retaining the core within 80 the tube and permitting the free withdrawal 85 of the fork B' therefrom.

This device for feeding the apple forward and retaining the core forms no part of my present invention, as it is described and claimed 90 in a separate application filed by me on the 29th day of August, A. D. 1881.

In order to facilitate the removal of the apple from the tube G after coring the same, I 95 secure the end of said tube to the upper end of an arm, J, which is pivoted to a lug on the

end of the frame A, coiled springs contained in barrels J' on the frame tending to maintain the tube in the horizontal position shown in Figs. 1 and 4, but permitting the elevation of the tube, as shown in Fig. 5, when it is desired to remove the apple therefrom.

In order to prevent the accidental elevation of the tube when the apple is first pressed against the end of the same and is not yet under the influence of the flange i, I provide the arm J with a pivoted catch, m, which, when the tube G is depressed, as shown in Fig. 4, engages with a lug, n, on the frame, the catch being readily elevated by means of the finger, so as to free it from the control of said lug when it is desired to elevate the tube. A stop, n', prevents undue movement of the arm J in either direction. The lower part of the tube G is cut away at t, so as to form an opening, through which the cores can drop into a suitable receptacle.

The slicing-knife H is not secured rigidly to the frame A, as usual, but is clamped at the lower end between a projection, w, on the frame A and a plate, w', the latter being acted upon by a screw, t, which passes through an opening in the knife and is adapted to a threaded opening in the plate w'. By this means the knife can be held in the vertical position shown in Figs. 1 and 2 when in use, or can, upon loosening the plate w', be turned down to the position shown in Fig. 3, so as to be out of the way when the slicing of the apple is not required.

It will be seen that with the above machine the apple can be pared, cored, and sliced, can be pared and cored without slicing, can be cored and sliced without being pared, or can be cored without being either pared or sliced.

The paring-knife which I use has a cutting-edge, comprising two portions, x x', arranged at an angle in respect to each other, as shown in Figs. 6 and 7, the portion x acting on the first half of the apple and the portion x' upon the last half, so that a flat and narrow cutting-blade is always presented and a narrow paring is insured, the removal of portions of the meat of the apple with the paring, as in the case of a broad knife, being prevented.

In order to effect the removal of the paring from that portion of the apple close to the stem, I secure to the frame A a fixed knife, M, the upper end of which is preferably curved, as shown in Fig. 1, the apple when first applied to the fork having a complete turn imparted to the same while it is in contact with the knife. This fixed knife, however, forms no part of my present invention, as it is described and claimed in Griscom's Patent, No. 168,985, dated October 19, 1875.

It will be observed, on reference to Fig. 1, that the clamp A' of the frame A is beneath the coring-tube G, so that when the machine is applied to a table or other support the paring devices are outside of or beyond the edge of the same, and the parings fall clear of the table and upon the floor or into a receptacle properly placed, the mixing of the sliced apple, parings, and cores being prevented.

I claim as my invention—

1. The combination of the frame A, fork-shaft, the coring-tube, and the paring devices with the cam-lever F, whereby the latter are thrown out of gear, as set forth.

2. The combination of the frame and fork-shaft with the coring-tube G, and its arm J, journaled to the frame and acted upon by a spring, as set forth.

3. The combination of the frame and fork-shaft with the coring-tube G, its arm J, journaled to the frame, and the pivoted retaining-catch m, as set forth.

4. The combination of the knife H, the frame A, having a projection, w, the thumb-screw t, and the clamp-plate w', between which and the projection w the knife H is confined, as set forth.

5. The within-described paring-knife, having a cutting-edge, comprising two narrow flat portions, x x', arranged at an angle in respect to each other, as set forth.

In testimony whereof I have signed my name to this specification in the presence of two subscribing witnesses.

ADOLPH RIPPEN.
